UNITED STATES PATENT OFFICE.

EDMUND C. MORGAN, DECEASED, BY OLIVE EUGENIE MORGAN, EXECUTRIX, OF NEW YORK, N. Y.

COAL-MINE ROOF-SUPPORTING MECHANISM AND MEANS FOR OPERATING THE SAME.

Application filed September 4, 1923. Serial No. 680,954.

The invention relates to mechanism for supporting roofs in mines for the purpose of controlling the subsidence thereof, and mechanism for operating roof props to shift them into new positions adjacent the space where mining operations are being carried on.

The object of the present invention is the provision of improved sectional roof-supporting mechanism.

10 A further object of the invention is the provision of improved and efficient means for releasing, shifting and positioning sectional roof-propping mechanism for the purpose of protecting the space where mining operations are being carried on and controlling the subsidence of the roof over the area from which the mineral has been removed.

More particularly it is the object of the 20 present invention to provide hydraulically-operated mechanism for releasing, shifting and positioning a series of adjacent roof props in a coal mine chamber adjacent the space where mining operations are being carried on to protect such space and control the subsidence of the roof on the opposite side of the series of roof props by establishing a predetermined break line.

Another object of the invention is the provision of mechanism for exerting hammer blows to effect the operation of roof prop-ping apparatus.

Other objects of the invention will appear hereinafter, the novel features and combinations being set forth in the appended claims.

Referring to the accompanying drawings, Fig. 1 is a plan view of the improved mechanism for operating sectional roof props;

Fig. 2 is an enlarged sectional elevation of Fig. 1 with the addition of portions of roof-propping mechanism shown in elevation; said sectional elevation being on the line 2—2, looking in the direction of the arrow;

Fig. 3 is a sectional elevation of Fig. 1 on the line 3—3, looking in the direction of the arrows, with the addition of a series of roof props and a pair of roof jacks spaced apart and located at the sides of the machine;

Fig. 4 is a sectional elevation of Fig. 1 on the line 4—4, looking in the direction of

the arrows, and also in elevation a portion of the roof-propping mechanism;

Fig. 5 is a sectional fragmentary view, 55 taken on the line 5—5 of Fig. 1, looking in the direction of the arrows;

Fig. 6 is an enlarged sectional view of one of the pump cylinders to show the valves and passages controlled thereby; 60

Fig. 7 is an enlarged sectional view on the line 7—7 of Fig. 1, looking in the direction of the arrows;

Fig. 8 is a plan view showing diagrammatically a series of roof props extending 65 across a space from which the coal vein has been removed adjacent the coal faces, with means located at intervals for shifting the roof props gradually to a new line or series; and

Fig. 9 is an elevational view of the roof prop operating mechanism in position for operating the sectional roof props, two of which are shown in elevation.

By referring to Fig. 1 it will be seen that 75 the supporting frame 10 carries an electric motor 11, which is provided with a shaft 12 journaled at its outer end in the bearing 13. Mounted on the shaft 12 is a pinion 14. The latter is loose on the shaft 12, but may be connected to rotate therewith by means of the clutch 15, which is operable by the lever 16 pivoted to the frame 10 at 17, as shown in Fig. 3.

As shown in Figs. 2 and 3, the frame 10 is adapted to be mounted on and supported by the rearward extensions 18 of the lower sections 19 so that such frame 10 may slide along laterally on the extensions 18.

The mechanism for shifting the frame 10 laterally along the extension 18 and transversely thereof, is shown in Figs. 1 and 3. This mechanism comprises roof jacks 20 and 21, which are placed on opposite sides of the supporting frame 10. A rope 22 is secured at its ends to the roof jacks 20 and 21 and intermediate its ends this rope is wound on the drum 23 which is journaled in the bearings 24 and 25 on the frame 10. When the clutch 12 is thrown in to transmit power from the motor 11 the pinion 14 will be rotated to operate the gears 26, 27 and 28 to rotate the drum 23 and thereby shift the frame 10 laterally, transversely of

the extensions 18 of the lower roof prop sections. By reversing the electric motor 11 the rotation of the drum 23 may be reversed to shift the frame 10 in the opposite direction.

- 5 It will thus be seen that by providing the electric motor 11 with a well-known starter and controller the frame 10 may be started, stopped or reversed, as desired. However, after the motor has been started in a certain 10 direction it is preferred to use the clutch 12 for operating the drum 23 intermittently to shift the frame 10 forward, step-by-step. A guide pulley 29 may be pivoted at 30 on the frame 10 to direct the rope 22 through 15 an opening 31 in the auxiliary frame 32, which is mounted on and rigidly secured to the frame 10 or may be made integral therewith, as shown in Fig. 3, so as to move bodily with the frame 10.
- 20 A foldable operator's platform 33 may be pivotally connected at 34 and 35 to the lower rear edge of the frame 10, 32, as shown in Fig. 1. As shown in Fig. 2 an abutment lug 36 may be associated with hinge so as to 25 hold the operator's platform 33 in horizontal position above the ground level 34.

The auxiliary frame 32 is provided with a lower extension 37 which is adapted to abut against the rear end 38 of the roof prop 30 extension 18. The forward portion of the frame 32 is provided with a foot 39 which is adapted to rest on top of the extension 18. The rear portion of the frame 10, 32 rests on the rear end 38 of extension 18, whereas 35 the forward portion of such frame is provided with feet 39 and 40 which rest on the upper horizontal plane surface of the extensions 18.

40 Mounted in the auxiliary frame 32 is a hydraulic ram comprising concentric hydraulic cylinders telescoping into each other. One of these cylinders 41 is connected to a travelling tertiary frame 42 which is adapted to be guided along the guide grooves 43 and 44 in the vertical walls 45 and 46 of the auxiliary frame 32.

Surrounding the cylinder 41 is another 45 cylinder 47 which is secured, by means of the cross-piece 48 and the bolts 49, to the walls 45 and 46. The cylinder 47 is provided with a gasket 50 to secure a hydraulic fit on the exterior of the cylinder 41. An entry port for the fluid pressure medium is provided at 51 between the inner ends of the 55 cylinders 41 and 47.

Movable into the cylinder 41 is a plunger 52, which is secured rigidly at 53 to the inner vertical front wall of the auxiliary frame 32. A stuffing box is provided at 54 on the cylinder head 55 of the cylinder 41 to surround the plunger 52. A port is provided at 56 to introduce the pressure medium into the passageway 57, which leads through the plunger 52 into the cylinder 41.

60 65 It will thus be seen that when pressure

medium is introduced into the passageway 57 and the port 51 is open to exhaust, the tertiary frame 42 and the parts carried thereby will be moved to the left, as viewed in Fig. 2, while guided along the grooves 43 and 44 between the spaced-apart vertical walls 45 and 46 of the auxiliary frame 32. When pressure medium is introduced into the port 51 and the port 56 is open to exhaust, the cylinder 41 and the tertiary frame 42 will be moved to the right, as viewed in Fig. 2, relatively to the frame 32, between the walls 45 and 46, while being guided by the grooves 43 and 44. It should be understood that the rock-shafts 58 and 59 are mounted on the frame 42 to project, respectively, into the grooves 43 and 44 in the wall 46 and that another pair of slots or grooves in the wall 45, similar to the pair designated 43, 44, receive the other ends of the rock-shafts 58 and 59.

60 The rock-shaft 58 is provided with an arm 60 which is connected to a rope 61, the latter extending over a pulley 62 to a weight 63 at its free end. Also connected to the rock-shaft 58 is a long and powerful pawl 64 which, when in lowered position, is adapted to rest in the pocket 65.

65 The rock-shaft 59 is provided with a crank-arm 66 to which is secured one end of a rope 67, the other end of which extends around the pulley 62 and is secured to the weight 68. Also connected to the rock-shaft 59 is a powerful elongated pawl 69, which, when in its upper position, rests in the pocket 70. The weight 68, by exerting a pull on the rope 67, may normally hold the pawl 69 counter-balanced so that it will be easy for the operator on the platform 33 to effect 70 the lifting, or lowering, of the pawl 69 according to whether it is to move into the notch 71 at the rear end of one of the roof prop extensions 18. When the operator pulls down on the weighted handle 68 the pawl 69 may be moved entirely into the pocket 70 so as to clear with certainty the notch 71. In a similar manner when the operator moves the weighted handle 68 upwardly the pawl 64 may be lowered by its own weight into the pocket 65 so as to clear 75 with certainty the notches 72, 73 and 74 in the upper extension 75 of the upper roof prop shoe 76. When a downward pull is exerted on the weighted handle 68 the pawl 64 may be easily moved upwardly so as to engage one of the notches 72, 73 or 74.

80 Another pawl-operating device is located on the frame 10 in the position shown in Fig. 1. This pawl-operating device comprises a standard 77 secured to the frame 10 and provided with a guideway 78 to receive the block 79. As shown in Fig. 4, this block 79 is provided with a depending projection 80 having a screw-threaded opening there-through adapted to receive the threaded 85 90 95 100 105 110 115 120 125 130

shaft 81 which has a retaining collar 82 at one end and a wheel-operating nut 83 at the other end. A pawl 84 is mounted on a rock-shaft 85 in a pocket 86. The pawl 84 may be lifted or lowered by means of the lever 87.

The pawl 84 may be used to engage one of the notches 72', 73' or 74' of an upper rearward extension of an anchored roof prop 75' having the upper roof-engaging shoe 76'.

Fig. 7 is a sectional view of Fig. 1 on the line 7—7, looking in the direction of the arrows, but enlarged to better illustrate the details of construction. An upper extension 88 from the frame 10 forms a standard for guiding the abutment block 89, which fits into and is slideable vertically in the pocket 90. The block 89 has secured thereto a screw-threaded rod 89' which is provided 20 with a wheeled-nut 92 which is adapted to effect the lifting and lowering of the block 89. When in lowered position, as shown in Fig. 7 it forms an abutment back of the rear end 38' for one of the extensions 18. By 25 referring to Fig. 1 it will be seen that the wheel 92 is located approximately opposite the rear end of the cylinder head 55, when the latter is in the position shown in Fig. 2. As will be later more fully explained, the 30 abutment 89, fitting against the rear end of a lower section of an anchored roof prop, will hold the frame 10 against movement toward the left, as viewed in Fig. 1, whereas the pawl 84, fitting into a notch 72', 73' 35 or 74', of an upper extension of an anchored roof jack, will hold the frame 10 against movement toward the right, as viewed in Fig. 1. Since the frame 10 is thus locked against movement toward the right or 40 toward the left, as viewed in Fig. 1, the hydraulic ram mechanism shown in Fig. 2 may be operated in either direction against the stationary auxiliary frame 32 which is rigidly connected to the frame 10. When 45 the roof props are to be tightened the pawl 64 is lifted so that when the frame 42 is moved toward the right the upper extension 75 will be moved toward the right to cause the inclined portion 90 to ride up on the inclined surface 91 and thus wedge apart the roof-propping sections while the lower section is kept from moving toward the right, as viewed in Fig. 2, by the abutting connections 37, 38, since the frame 32 is locked 50 against movement toward the right and toward the left by the pawl 84 and the abutment block 89.

By referring to Fig. 1 it will be seen that the frame 32 is provided with a lock or abutment 93 which is adapted to abut against the floor shoe or base frame of an adjacent anchored roof prop. That is to say, while the downwardly projecting extension 37 as shown in Fig. 2 abuts against the rear end of 65 the floor shoe of a roof prop to be operated,

the lateral projection 93 abuts against the rear end of the floor shoe of an anchored prop. By means of this the floor shoes are arranged in a horizontal series parallel to the working face 94, as shown in Fig. 8. 70

The system of mining is diagrammatically illustrated in Fig. 8. Entries 95 are driven at right angles to the working faces 94 so as to form pillars of coal 96. Mining operations are carried on along the working faces 75 or rear ends of the coal pillars and the mined coal transported out of the mine along the entries 95. The series of parallel roof props are shown at 97 extending from the wall 98 to the wall 99. The space 100 represents the 80 area from which the coal has been mined and in this space the coal may be permitted to subside. The series 97 of roof props controls such subsidence by forming a break line indicated at 101, which is at the rear end of the roof shoe as shown in Fig. 9. In any event the roof is supported by the series of roof props so that no subsidence can occur except at the break line 101 or back of the 85 same, and therefore the space 102 where mining operations are being carried on is amply protected. It should also be noted that the rear upper surfaces 103 of the base frames are inclined downwardly and rearwardly to form an inclined plane which is 90 continuous from the wall 98 to the wall 99 and which assists in causing subsided coal to move toward the space 100. 95

At 104 in Fig. 8 are represented diagrammatically a plurality of roof prop operating devices of the type illustrated in Figs. 1 and 3. These operating devices may each be operated independently of the others so that a number of roof props may be released at the same time and moved forwardly and anchored in new positions. However, the forward movement of the roof props is always gradual in that the remaining roof props continue to be anchored until the forwardly moved roof prop is reanchored. That is to say, the percentage of released roof props is always small and the shifting of the roof props to new positions and the reanchoring of the same to form a new series always takes place gradually. Therefore space 102 105 where the mining operations are being carried on is always fully protected. 110

In some instances the coal veins may be comparatively narrow, in which event the platform 33 is particularly useful for the operator to lie on or rest on in a kneeling or crouching position. 115

To facilitate movement of the frame 10 over the mine floor an adjustable skid 105 is pivoted at 106 to the platform 10, as shown in Figs. 1 and 5. By means of the worm and worm wheel gearing 107 the skid 105 may be moved from the full line position shown in Fig. 5 to the broken line position shown at 108. In the latter position the 120 125 130

skid 105 supports the platform in elevated position independently of the floor shoes. The skid 105 not only facilitates movement of the frame 10 and the parts mounted thereon, over the mine floor into position for operation; but also tilts upwardly the platform 10 so as to initially permit one of the floor shoes to be moved under the frame 32 while the extension 37 still rests on the mine floor, and while the platform 33 is folded to a vertical position. The skid 105 is located midway between the sides of the machine shown in Fig. 1 so that ample space is provided under the frame 32 for insertion of the floor shoe 18. When a notched shoe is also in position the hydraulic motor may be operated so as to engage one of the notches 72, 73 or 74, whereupon the frame 32, together with the platform 10, will be moved up on the shoe 18 until the extension 37 abuts against the rear end 38 of the floor shoe.

The base frame 19, as shown in Fig. 2, has secured to the upper side thereof a bracket 109 which is provided with an inclined trough to receive the lower inclined surface of the upper frame which carries the roof shoe 76. By reference to Fig. 9 it will be seen that when the hydraulic motor moves the roof and floor shoes horizontally in opposite directions relatively to each other the roof prop will be expanded to secure anchoring of the same. That is to say, while the floor shoe is stationary and the hydraulic motor operates to slide the roof shoe in a horizontal direction along the roof the framework between the floor and roof shoes is expanded to secure a wedging effect, thereby anchoring the floor and roof shoes firmly between the floor and roof of the mine chamber.

When the supporting framework between the floor and roof shoes is expanded to secure anchoring of the roof prop the resistance increases as the shoes are being anchored. It is therefore desirable to operate the hydraulic motor with hammer blow when a predetermined resistance is reached. After the roof props have been anchored the roof tends to subside, thereby clamping together the triangular frames with even greater force than that exerted thereon to secure anchoring of the floor and roof shoes, since the surface contact between the triangular frames is at such an angle that it will be difficult to overcome the frictional engagement between such surfaces. However, on account of the difficulty under such circumstances of releasing the roof props against such frictional contact it is also desirable to operate the motor with a hammer blow to release the floor and roof shoes.

To secure such hammer blow to operate the roof props the system of valves shown in Fig. 6 is provided. By referring to Figs.

1 and 2 it will be seen that a pressure supply pipe 51' leads to the port 51 between the cylinders 48 and 41. A pressure supply pipe 56' leads to the port 56, which is connected to the passageway 57 extending through the plunger 52. The valve 110 may be located in the pipe 51' and the valve 111 in the pipe 56'. The shaft 12 of the motor 11 carries a worm 112 which meshes with the worm gear 113 mounted in the casing 114. At the ends 75 of the shaft 115 of the worm gear 113 are oppositely extending cranks 116 and 117 which are connected by the links 118 and 119 respectively to the pump cylinders 120 and 121. The pumping mechanism may be of 80 any well known type adapted to pump a liquid from a tank into the pipes 122 and 123. It should be understood that the valves 110 and 111 are each three-way valves so that when in one position one will be connected 85 to the supply and the other to the exhaust. For instance, when the valve 110 is in such a position that the pump will force the liquid through the pipe 122 into the pipe 51' the 90 exhaust pipe 124 will be closed. At the same time the valve 111 will be in such a position that the pipe 56' will be connected to the exhaust pipe 125 and the supply pipe 123 will be closed. The arrangement is such 95 that when the pump is operated the fluid pressure medium may be forced into port 51 shown in Fig. 2 to spread apart the cylinders 48 and 41, while at the same time the port 56 will be connected to exhaust so that as the cylinder 41 moves toward the right the pressure medium in the latter may be forced 100 through the passageway 57. Likewise when the pressure medium is supplied to the port 56 and the cylinder 41 moves toward the left the liquid in the cylinder 48 is exhausted 105 through the port 51.

As shown in Fig. 6, the piston 126 when moved upwardly will draw into the port 127 the liquid from the source of supply and this liquid is free to pass the check valve 128 into the chamber 129 of the cylinder 120. As the piston moves down the check valve 128 is closed, and check valve 130 is opened against the action of the spring 131 and the liquid is forced through the passageway 132 into the pipe 122 and thence through the valve 110 and the pipe 51' to the port 51. The pumping action may be continued until the back pressure due to the anchoring of the roof prop becomes sufficient to operate the valve 133. In Fig. 6 a passageway 134 is shown communicating with the passageway 132. When the pressure in passageway 134 on the piston 135 is sufficient to overcome the spring 136 the valve 133 will be closed shutting off communication between the supply port 127 and the passageway 137. When this occurs the pump piston 126 is still in operation and therefore the liquid 120 will constantly act as an abutment and cause 125 130

the motor to exert a hammer blow to very powerfully and quickly move the roof shoe horizontally along the mine roof to secure an extra squeezing of the floor and roof shoes into roof proping positions. It should be understood that the pump 121 may be also provided with the valve arrangement shown in Fig. 6 so that when the floor shoe is to be moved horizontally along the floor by the 10 pawl 69 an extraordinary effort may be made to secure the release of the roof prop by the hammer blow action due to the closing of the valve 133 when the pressure in the passageway 134 reaches a predetermined 15 amount. An additional safety valve may be placed in a by-pass pipe leading from the pipe 122 to the tank or source of supply. That is to say, in a by-pass from the pipe 122 to the source of liquid may be located a 20 check valve set to be opened when the pressure in the pipe 122 exceeds a predetermined amount so that continued movement of the piston 126 will not injure the mechanism by securing a greater hammer blow than desired, but will permit the excess pressure to force the liquid through the by-pass check valve to the tank having a supply of liquid.

By referring to Fig. 3 it will be seen that the base frames for the floor shoes are hollow so as to save material and to lighten their construction, as they are preferably made of metal. They are self sustaining in that they will rest on the floor by gravity without assistance and also support the upper frames 90 while the latter at the horizontal portions of the roof extensions engage the brackets 109. As shown at 138 in Fig. 3, the upper frames are in reality narrow plates as compared with the roof shoes 76. The elongated roof and floor shoes with larger shoes spread laterally to widths approximately equal to the widths of the floor shoes enables the series of roof props to be extended over a wide area, as shown in Fig. 45 8, and thus more effectively support the roof and protect the space where mining operations are being carried on. Furthermore, the open spaces 139 of Fig. 3 between the vertical plates 138 afford large open passageways between the space 100 of Fig. 8 and the working space 102. Therefore, notwithstanding the arrangement of the roof props from one wall 98 to the other wall 99, ventilation will not be interfered with, and if 50 the subsidence of the roof in the space 100 causes a sudden rush of air the spaces 139 will facilitate such rush of air into the entries 95.

Obviously those skilled in the art may make various changes in the details and arrangement of parts without departing from the spirit and scope of the invention as defined by the claims hereto appended, and it is therefore desired not to be restricted to the precise construction herein disclosed.

Having thus fully described and shown an embodiment of the invention, what is desired to be secured by Letters Patent of the United States is:

Claims:

1. In mine roof-supporting mechanism, the combination with an elongated floor shoe adapted to rest on and move over a mine floor, of an elongated roof shoe adapted to engage the roof of a mine chamber, frames 70 slidably connected together on an incline and carrying said shoes in position to respectively engage the floor and roof of the mine chamber, a self-contained power-operated motor, and connections between said motor and said shoes for expanding the latter along such incline to cause said shoes to firmly grip the floor and the roof.

2. In mine roof-supporting mechanism, the combination with a roof shoe adapted to engage the roof of a mine chamber, of a floor shoe adapted to rest on and move over a mine floor, wedging connections between said shoes in position to expand said shoes respectively against the floor and the roof of the mine chamber, an operating motor for said wedging connections, and connections between said motor and said wedging connections to operate the latter.

3. In mine roof-supporting mechanism, the combination with a floor shoe adapted to rest on and move over a mine floor, of a roof shoe adapted to engage the roof of a mine chamber, interengaging wedging frames for carrying said shoes in position to respectively engage the floor and the roof of the mine chamber, an operating motor, and means for detachably mounting said motor between said shoes to operate said wedging frames to expand said shoes in supporting positions against the floor and roof.

4. In mine roof-supporting mechanism, the combination with a roof shoe adapted to engage the roof of a mine chamber, of a floor shoe adapted to rest on and move over a mine floor, triangular frames for carrying said shoes in position to respectively engage the floor and the roof of a mine chamber, inclined interengaging sliding connections between said frames to effect wedging action between said frames and thereby anchor said shoes respectively against the floor and the roof of the mine chamber, a motor, and connections for said motor to enable the latter to act on said interengaging sliding connections in opposite directions to expand said shoes into their anchoring positions.

5. In mine roof-supporting mechanism, the combination with a floor shoe adapted to rest on and move over a mine floor, of a roof shoe, expandible mechanism between said shoes for operating the same to anchoring positions, a motor having a frame abutting against one end of one of said shoes,

and a connection between said motor and the other shoe for effecting the actuation of said expansible mechanism to operate the same as aforesaid.

5 6. In mine roof-supporting mechanism, the combination with a floor shoe adapted to rest on and move over a mine floor, of a roof shoe, expansible framework between said shoes, a motor, and connections between 10 said motor and said shoes to move the same longitudinally in opposite directions and thereby operate said expansible framework to force said shoes firmly into anchored positions against the floor and the roof of 15 the mine chamber.

7. In roof-supporting mechanism, the combination with an elongated hollow self-supporting base frame having an upper inclined surface, of an elongated roof-engaging 20 shoe having a width at the roof approximately equal to the width of the said frame at the floor, a second frame having a lower inclined surface fitting said upper inclined surface, and a narrow connecting plate between 25 said frame and said roof-engaging shoe to afford air spaces below the roof shoe on both sides of said narrow plate.

8. In mine roof supporting mechanism, the combination with a base frame having a 30 floor shoe, of a roof shoe, interengaging mechanism between said roof shoe and said frame for spreading apart said shoes to operate the same against the floor and roof of the mine chamber, and a notched extension 35 on one of said shoes in position to have connected thereto a motor for operating said interengaging mechanism.

9. In mine roof supporting mechanism, the combination with a base frame having a 40 shoe adapted to rest on and move over a mine floor, said base frame having an upper inclined surface, a second frame having a roof-engaging shoe and a lower inclined surface fitting said upper inclined surface, and detachable self-contained power-operated 45 apparatus adapted to be connected to one shoe and abut against the other to slide the shoes in parallel opposite directions to cause said inclined surfaces to spread the shoes 50 apart to anchored positions between the floor and the roof of the mine chamber.

10. In mine roof supporting mechanism, the combination with an elongated base frame having a floor shoe and an upper inclined surface, of an elongated roof shoe 55 parallel to said floor shoe, a second frame for carrying said roof shoe and having a lower inclined surface fitting said upper inclined surface, a horizontal extension on one 60 of said shoes provided with means for the application of power to slide the shoe relatively in opposite directions to cause said frames to expand and anchor said shoes, and a portable detachable operating device 65 abutting against one end of one of said

shoes and connected to the aforesaid means of the other shoe to effect said application of power to operate said shoes.

11. In mine roof supporting mechanism, the combination with an elongated roof shoe, of an elongated floor shoe, expansible framework mechanically connecting said shoes, horizontal extensions on said shoes with a free and unobstructed space between them for the positioning of power-operated mechanism, and means on said extensions to adapt them to receive the application of mechanical power from such power-operated mechanism to mechanically operate said framework to in turn operate said shoes.

12. In mine roof supporting mechanism, the combination with a floor engaging shoe, of a roof engaging shoe, expansible framework between said shoes, parallel extensions from the rear ends of said shoes with a free and unobstructed space between such extensions, and means on said extensions adapting the same for connection thereto of apparatus for operating said expansible framework to anchor said shoes.

13. In mine roof supporting mechanism, the combination with a roof prop comprising expansible supporting framework, of parallel spaced-apart extensions from the roof prop along the floor and roof respectively with a free and unobstructed space between the same, and detachable means extraneous to said framework but adapted to be connected to said parallel spaced-apart extensions for operating the expansible supporting framework and thereby effecting the operation of the roof prop.

14. In mine roof supporting mechanism, the combination with a roof prop comprising expansible supporting framework, of parallel spaced-apart extensions from the roof prop along the floor and roof respectively, and means for exerting forces on said extensions horizontally along the roof and floor and approximately parallel thereto to operate said framework to anchor said roof prop.

15. In mine roof supporting mechanism, the combination with a roof prop comprising expansible framework, of parallel spaced-apart extensions connected to said framework, and detachable power-operated mechanism connected to said extensions to move the same relatively in opposite directions parallel to the floor and roof respectively to cause said framework to expand in a direction at right angles to the floor and roof.

16. In mine roof supporting mechanism, the combination with a roof prop elongated in a direction parallel to the roof and floor of a mine chamber and comprising expansible framework, and detachable means connected to said framework to act thereon in opposite directions parallel to the roof and

floor to expand said framework and anchor the roof prop.

17. In roof-supporting mechanism, the combination with an expansible roof prop, 5 of oppositely movable notched extensions along the floor and roof respectively, and means adapted to engage said extensions to move the same in opposite directions and thereby operate said expansible roof prop.

18. In mine roof supporting mechanism, the combination with a base frame having a floor shoe, of a roof shoe, expansible mechanism connecting said base frame to said roof shoe, and means adapted to abut against 15 one end of the base frame and the under side of the roof shoe and slide the latter along the roof to actuate said expansible mechanism to anchor said shoes to the floor and roof of the mine chamber.

19. In roof-supporting mechanism, the combination with a base frame having a floor shoe, of a notched extension of the floor shoe, a roof shoe, a notched extension of the roof shoe, expansible means between said 25 frame and said roof shoe, and means between said extensions for operating said expansible means to anchor or release said shoes from the floor and roof of the mine chamber.

20. In roof-supporting mechanism, the combination with a base frame having a floor shoe provided with a notch in its upper surface, at its rear portion, of a roof shoe having a notched lower surface at its rear portion, expansible mechanism between said 35 frame and said roof shoe, mechanism adapted to abut against the rear end of said roof shoe and engage the lower notched surface of said roof shoe to slide the latter along the roof and thereby operate said expansible mechanism to anchor said shoes, and auxiliary mechanism adapted to engage the notch in the lower shoe to slide the latter rearwardly to release the shoes from the floor and roof.

21. In an anchorage for mines, the combination with roof and floor-engaging shoes, of expansible wedge mechanism between the same, and mechanism for moving one shoe longitudinally parallel to the floor and 50 roof of the mine chamber to operate the wedge mechanism to anchor both shoes and for moving the other shoe longitudinally parallel to the floor and roof to release said wedge mechanism to effect the release of 55 both shoes.

22. In roof propping mechanism for mines, the combination with a plurality of elongated individual expansible roof props, of a portable frame having extensions adapted to abut against the rear end of a roof prop to be operated and also against the rear end of an adjacent anchored roof prop, and means on said portable frame for anchoring a released roof prop.

23. In roof-supporting mechanism, the combination with a plurality of parallel elongated roof props each comprising roof and floor-engaging shoes with intervening expansible mechanism, of a portable frame adapted to abut against the floor shoe of 70 roof prop to be anchored and an adjacent floor shoe of a previously anchored prop, and means mounted on said portable frame to slide the roof shoe of the released roof prop to operate said expansible mechanism 75 and anchor such last named prop.

24. In a roof-supporting mechanism, the combination with a roof prop comprising roof and floor-engaging shoes and intervening expansible mechanism, of an actuating device comprising a manually controlled pawl for engaging one of said shoes, and means for controlling the said actuating device to secure the anchoring of said roof prop.

25. In roof-supporting mechanism, the combination with a roof prop comprising floor and roof engaging shoes and wedging mechanism between the same, of a horizontally operable hydraulic motor, and means 90 operated by said motor to effect the operation of said wedging mechanism.

26. In mine roof supporting mechanism, the combination with a roof prop comprising floor and roof engaging shoes with intervening mechanically operated expansible means, of a portable motor, and connections for said motor to said expansible means to exert forces thereon in opposite directions parallel to the floor and roof to mechanically operate said expansible means to anchor said shoes to the floor and roof of the mine chamber.

27. In roof-supporting mechanism, the combination with a plurality of roof props adapted to be placed in a row adjacent each other successively, and each comprising roof and floor engaging shoes and intervening expansible means entirely mechanical, a portable motor adapted to be moved along said roof props transversely thereof, and connections between said motor and each of said roof props for operating the latter to anchored and released positions and to positions to form a new row of such roof props.

28. In roof-supporting mechanism, the combination with a series of individual roof props in a row to form a roof support extending over a wide area and each comprising elongated floor and roof-engaging shoes with expansible wedge mechanism intervening, a portable motor movable along the series transversely of the roof props, and connections to effect sliding of the shoes along the floor and roof to release the same and move the same into new positions and anchor the same in such new positions to form a new series of such roof props.

29. In a system of roof supporting mechanism adapted to control the subsidence of 130

the roof into the space where mining operations have been completed, the combination with a series of individual elongated roof props each comprising elongated floor and 5 roof-engaging shoes with intervening expansible means entirely mechanical, of a plurality of portable motors each movable along such series of roof props, and connections adapting each of said motors to release 10 any one of said roof props, move the same into a new position and anchor the same in such new position to form a new series of such roof props.

30. In a system of mining comprising 15 roof-supporting mechanism arranged to control the subsidence of the roof into the space where mining operations have been completed, the combination with a series of closely adjacent roof props comprising floor 20 and roof-engaging shoes with a plurality of air passages from one side of the series to the other to permit free passage of air through the series when the roof subsides on one side thereof, of a portable motor, and 25 means operated by said motor for individually releasing said roof props, moving the same into new positions and anchoring the same in such new positions to form a new series of such closely adjacent roof 30 props.

31. In roof-supporting mechanism, the combination with a portable frame, of a series of roof jacks, each comprising a roof shoe and a floor shoe, an abutment on said 35 frame in position to engage the rear end of one of the floor shoes, an additional abutment on said frame to engage one of the roof shoes, said abutments co-acting to prevent movement of said frame in either direction longitudinally of the jacks, and mechanism mounted on said frame in position to be connected to the roof jacks individually to operate them by releasing them, shifting them and anchoring them.

40. 32. In roof-supporting mechanism, the combination with a series of elongated roof jacks adapted to be placed in parallelism in a series to form a break line to control the 45 subsidence of the roof into the space where mining operations have been completed, each of said roof jacks comprising an elongated floor shoe and a notched elongated roof shoe, of a portable frame movable along the floor 50 shoes, an abutment adapted to be thrust from the bottom of said frame into position back of an anchored floor shoe of one of the roof jacks, adjustable mechanism adapted to be 55 thrust into a notched roof shoe of another roof jack to co-act with said abutment to hold the frame against movement longitudinally of the roof jacks, and mechanism mounted on said frame in position to release a roof jack, move the same to a new position and anchor the same in such new position.

60. 33. In roof-supporting mechanism, the

combination with a portable frame, of rope winding mechanism mounted thereon and comprising ropes the free ends of which are adapted to be anchored in the mine, a series of roof jacks, means on said roof jacks for 70 guiding said frame, a motor for driving said winding mechanism, fluid pressure mechanism on said frame for operating said roof jacks, and a pump operated by said motor for supplying fluid pressure medium to said 75 fluid pressure mechanism.

34. In roof-supporting mechanism, the combination with a roof prop comprising floor and roof shoes with intervening expansible mechanism, of a fluid pressure motor for operating said roof jacks, and pumping mechanism for supplying pressure medium to said motor and exerting a hammer blow at a predetermined accumulated pressure.

35. In roof-supporting mechanism, the combination of a roof prop comprising floor and roof shoes and intervening expansible mechanism, and means for exerting a hammer blow on said expansible mechanism to 90 release said shoes.

36. In roof-supporting mechanism, the combination with a roof prop comprising floor and roof shoes and intervening expansible mechanism having inclined contacting 95 wedging surfaces, of means for operating said expansible mechanism to anchor or release said shoes, and mechanism coacting with said operating means to exert a hammer blow to tighten said shoes in anchored position or to release the same.

37. In roof supporting mechanism, the combination with a floor shoe, of a roof shoe, intervening expansible mechanism comprising triangular frames respectively 105 connected to said shoes to move therewith, said frames having inclined wedging contacting surfaces, motor mechanism for sliding said shoes relatively in opposite directions to cause said frames by said inclined surfaces to anchor said shoes, and means for effecting the application of an extra squeeze on said shoes when in anchored positions.

38. In roof-supporting mechanism, the combination with a roof shoe, of a floor 110 shoe, mechanical operating connections between said shoes, and portable detachable mechanism for operating said mechanical connections to actuate said shoes.

39. In roof-supporting mechanism, the combination with a roof shoe, of a floor shoe, mechanical operating connections between said shoes, and a portable motor adapted to be applied at will to operate said mechanical connections and actuate said shoes.

40. In mine roof supporting mechanism, the combination with a floor shoe, of a roof shoe, means comprising inclined engaging faces between said shoes for adjusting the relative positions of the latter, parallel pro-

jections from said shoes extending along the roof and the floor of the mine chamber, and detachable means adapted to rest on one of said projections and engage the other projection overhead to effect relative movements of said engaging faces to anchor said shoes.

41. In mine roof supporting mechanism, the combination with a floor shoe, of a roof shoe, inclined wedging connections between said shoes, elongated extensions of said shoes on the same side of said connections, and means adapted to be applied to said extensions and between the same to move the latter in opposite directions relatively and respectively along the floor and roof of the mine chamber to operate said wedging connections to secure the application or release of said shoes.

42. In mine roof supporting mechanism, the combination with roof and floor shoes, of mechanical actuating connections between the same, a hydraulic motor, a frame for supporting said motor, a connection between said frame and one of said shoes to prevent movement of said frame relatively to the last-named shoe, and a connection between said motor and the other shoe to secure movement of the shoe in a direction parallel to the roof and floor upon the operation of said motor.

43. In mine roof supporting mechanism, the combination with floor and roof shoes, of actuating means between the same, a hydraulic motor, a frame for supporting said motor, means for holding said frame stationary relative to one of said shoes, and a connection between said motor and the other shoe to exert a positive direct force thereon to operate said actuating means to anchor both of said shoes between the floor and the roof of the mine chamber.

44. In mine roof supporting mechanism, the combination with floor and roof shoes, of actuating connections between the same, a motor having a frame connected to one shoe for the latter to serve as an abutment, and a connection between the motor and the other shoe to cause the motor to exert forces on said shoes in opposite directions parallel to the roof and floor to effect the anchoring of said shoes.

45. In mine roof supporting mechanism, the combination with floor and roof shoes, of actuating connections between the same, a motor having a frame with an abutment engaging one of said shoes, a lateral abutment on said frame serving to engage an adjacent anchored roof support to aline said floor shoe laterally with the floor shoe of the anchored roof support, and a connection between said motor and said roof shoe to operate said actuating connections when said motor is operated.

46. In mine roof supporting mechanism, the combination with a floor shoe, of a wide-

ly expanded horizontal flat roof shoe, a narrow plate depending from the horizontal flat roof shoe to afford air spaces below the horizontal roof shoe on both sides of said narrow plate, and anchoring connections between said plate and the floor shoe.

47. In mine roof supporting mechanism, the combination with a multiplicity of floor shoes adapted to be placed side by side in a series, of a corresponding multiplicity of roof shoes respectively above the floor shoes, each of said roof shoes being widely expanded into a horizontal flat roof engaging surface and said roof shoes being arranged successively closely adjacent to form a break line for the roof to subside into the space from which the mineral has been mined, a series of narrow supports one depending from each of said roof shoes to afford air spaces below the flat horizontal roof shoes between said narrow plates, and anchoring connections between the floor shoes and said narrow plates.

48. In mine roof supporting mechanism, the combination with a roof engaging shoe, of a floor engaging shoe, expansible framework between said shoes, an expansible motor adapted to be connected to said shoes to move the same relatively in opposite directions to operate said expansible framework to spread apart said shoes to anchor the same, mechanism for operating said motor, and a frame for supporting said motor between said shoes and said operating mechanism on a plurality of adjacent roof supports.

49. In mining apparatus, the combination with mechanism to be operated, of a frame, a hydraulic cylinder rigidly connected to said frame, a plunger rigidly connected to said frame with its axis coinciding with the axis of said cylinder, a hollow plunger fitting into said cylinder when in one position and over said rigid plunger when in its opposite position, the stroke of said hollow plunger being from its position in said cylinder to its position over said plunger, said cylinder and said plunger being rigid with said frame, mechanical connections between said hollow plunger and said mechanism to be operated, and means for controlling the operation of said hollow plunger.

50. In hydraulic motor apparatus, the combination with mechanism to be operated, of concentric cylinders one fixed and the other movable, a plunger fixed to one of said cylinders with its major portion spaced therefrom but with its axis coinciding with the axis of said fixed cylinder, said movable cylinder being adapted to move along and over said fixed plunger into and partially out of the said fixed cylinder, mechanical means on the movable cylinder for connection to said mechanism to be operated, and means for controlling the operation of said

movable cylinder relatively to said plunger and said fixed cylinder to effect the operation of said mechanism.

51. In mine roof supporting mechanism, the combination with an elongated self-supporting base frame having an upper inclined surface, of an elongated roof-engaging shoe having a width at the roof approximately equal to the width of the frame at the floor,

a second frame having a lower inclined surface fitting said upper inclined surface, and a narrow connecting plate between said frame and said roof-engaging shoe to afford air spaces below the roof shoe on both sides of said narrow plate. 10

OLIVE EUGENIE MORGAN,
Executrix of the Estate of Edmund C. Morgan, Deceased.
